ERNEST B. FREEMAN, OF DEDHAM, MASSACHUSETTS, ASSIGNOR TO B. F. STURTEVANT COMPANY, OF BOSTON, MASSACHUSETTS, A CORPORATION OF MASSACHUSETTS.

FUEL-ECONOMIZER.

1,074,855.

Specification of Letters Patent.

Patented Oct. 7, 1913.

Application filed November 25, 1908. Serial No. 464,464.

To all whom it may concern:

Be it known that I, ERNEST B. FREEMAN, citizen of the United States, residing at Dedham, in the county of Norfolk and State 5 of Massachusetts, have invented certain new and useful Improvements in Fuel-Economizers; and I do hereby declare the following to be a full, clear, and exact description of the invention, such as will enable others 10 skilled in the art to which it appertains to make and use the same.

The invention relates to fuel economizers or feed water heaters such as are employed to utilize the heat contained in waste products of combustion. These fuel economizers are usually constructed with upper and lower header sections, each upper section being connected with the corresponding lower section by a series of vertical pipes. The lower 15 header sections are in communication with each other through manifolds or wall boxes, to which each header is connected, and which are also connected together. The upper 20 header sections are in communication with each other, either directly through openings formed in the sides of the header sections, or through manifolds or branch pipes to which each header section is connected. In 25 economizers of this type as heretofore constructed it has been customary to provide for the expansion and contraction due to the variation in the temperature to which the apparatus is subjected, by employing gaskets in the joints between the directly communicating 30 header sections, or between the header sections and manifolds or branch pipes and between the sections of the manifolds. It has been found that under the high pressures used in modern practice, and under the wide 35 fluctuations in pressures and temperatures to which economizers are subjected, that these gasket joints are liable to give way or become defective, and the presence of such joints has come to be a serious defect in 40 economizer constructions.

It is accordingly one of the objects of the present invention to provide for the proper connecting together of the header and manifold sections without interfering with the necessary expansion and contraction of the 45 parts, and without the necessity of employing objectionable gasket joints.

To this end one feature of the invention 50 contemplates the provision in an economizer in which the header sections are in communica-

cation with each other through manifold or branch pipe sections, such communications being established by means of coupling pipes provided at their ends with joint seats adapted to engage joint seats in the headers and 55 manifolds respectively, and acting to connect each header with the manifold. In thus connecting the header sections and manifolds or branch pipes by coupling pipes, metal to metal taper joints may be employed, 60 which require no packing or gaskets. The use of such coupling pipes of different lengths also enables alternate header sections to be conveniently coupled with the manifold in economizers in which the vertical 65 pipes in succeeding sections are staggered or arranged so that the pipes in one section are opposite the spaces between the pipes in the adjacent section. The coupling pipes are preferably in the form of bends or 70 elbows, so that the joint seats at the ends of the pipes are not opposite or in register with each other, since such form of coupling pipe is well adapted to spring slightly to accommodate a relative movement of the parts 75 due to expansion and contraction. The use of this form of coupling pipe for connecting the header sections and manifolds also facilitates the accurate positioning of the header 80 sections to bring the circulating tubes in adjacent sections into proper relation for the 85 operation of the tube cleaning scrapers in setting up the apparatus. The pipes, headers and manifolds of economizers are made of cast iron, and the headers and vertical 90 pipes are assembled to form the sections of the economizer in the factory, these sections and the manifolds or branch pipes being assembled in setting up the economizer 95 where it is to be used. There are necessarily, therefore, inaccuracies or variations in the sections and in the coupling pipes. In setting up the economizer the coupling pipe for connecting any header section with the manifold may be selected which will bring 100 the vertical pipes in that section into proper relation with the vertical pipes in the adjacent section. That is to say, if the first coupling pipe tried does not bring the header section into the proper relative position, 105 other coupling pipes may be tried until one is found in which the joints at the end of the pipe are in proper relation to bring the header into its proper position.

A further feature of the invention con- 110

templates the provision in an economizer in which the header sections are in communication through a sectional manifold or branch pipe of a double coupling for connecting two adjacent header sections with 5 two adjacent sections of the manifold, and also connecting the sections of the manifold. This coupling is provided with four joint seats, two of which are arranged to engage 10 joint seats on two adjacent header sections, and the other two of which are arranged to engage joint seats on the adjacent ends of two manifold sections. In its preferred form, this coupling is in the form of two 15 bends or elbows communicating between their ends through a connecting pipe which is preferably cast integral with the two bends. With this construction, an expandable coupling is provided which may be connected with the header and manifold sections by metal to metal joints, and which is well adapted to spring or bend during the 20 contraction and expansion of the parts. The joint seats may be and preferably are 25 arranged to rotatively engage the parts to be coupled, and a tight joint is maintained during the contraction and expansion of the parts. The employment of this double coupling in connection with coupling pipes for 30 connecting the header sections to the manifolds or branch pipes also enables an economizer to be readily changed either in setting it up or after it has been installed, to secure either a "natural circulation" or a "forced 35 circulation" through the economizer. If a natural circulation through the economizer is desired, the double coupling is employed for connecting two adjacent header sections with the adjacent ends of two manifold sections. In this case the manifold sections are 40 in communication through the coupling, thus bringing all the header sections into communication with each other through the manifolds. This will give a natural circulation 45 through the economizer. If it is desired to change to a forced circulation, then the double coupling may be removed, and two single coupling pipes employed for connecting the two adjacent header sections 50 with the adjacent ends of two manifold sections. In this case the two adjacent manifold sections are not in communication, and the water in passing from one manifold section to another must pass through the vertical 55 pipes connected with the header sections, in which case a forced circulation is secured.

Further features of the invention relate 60 to certain features of construction and arrangement whereby various parts of the apparatus are rendered conveniently accessible, and whereby the upper manifold and the delivery pipes may be conveniently arranged and located in accordance with the 65 conditions under which the apparatus is to be installed.

The various features of the invention will be readily understood from an inspection of the accompanying drawings, in which—

Figure 1 is a transverse elevation partly in section showing an economizer embodying the various features of the invention in their preferred form; Fig. 2 is a plan view of the economizer shown in Fig. 1; Fig. 3 is a rear elevation of the upper part of the economizer; Fig. 4 is a vertical section 75 through the rear end of an upper header; and Fig. 5 is an elevation partly in section of the rear end of an upper header, showing a modified form of coupling pipe for connecting the upper header with the upper 80 manifold.

The economizer shown in the drawings comprises a series of lower headers 1, a corresponding series of upper headers 2, and series of vertical tubes 3 connecting each 85 lower header with its corresponding upper header. The lower headers are connected at their forward ends by manifolds or branch pipes 4, through which the lower headers are in communication with each other. The vertical pipes are connected with the headers and the lower headers are connected directly with the lower manifolds or branch pipes. This manner of connecting is fully 90 shown and described in the patent to Burpee, No. 729,273, May 26, 1903. Openings are formed in the upper headers directly 95 over the vertical pipes 3, and are closed by caps 5 in the manner shown and described in said patent.

Each upper header is provided at its rear end with an upward extension 6, in the upper end of which a tapered joint seat 7 is formed. Each header is connected with a rear manifold or branch pipe 8 by a coupling pipe 9, the ends of which are provided with tapered joint seats 10, one of which engages the joint seat 7 in a header, and the other of which engages one of a series of joint seats 11 formed in one side of the 105 manifold. The coupling pipe 9 is provided with flanges 12 adjacent to the joint seats 10, and the headers and manifolds are provided with flanges 13 and 14 adjacent to the joint seats 7 and 11 respectively. The joint seats 110 are drawn firmly together by bolts 15 which pass through holes in the flanges and are engaged by nuts 16. By this construction the upper headers are independently connected with the upper manifolds or branch pipes, 115 and metal to metal joints are provided which will effectively withstand high pressures while allowing the expansion and contraction of the parts caused by variations in temperature.

The extensions 6 are preferably formed directly over the rear tubes 3, so that the rear tubes may be inserted through the openings formed in the extensions, and so that these tubes may be readily accessible in case 120

it is necessary to remove them, by merely removing one of the coupling pipes 9. In the construction shown, provision is made for arranging the vertical pipes so that they 5 are staggered in adjacent sections by employing coupling pipes 9 of different length, as clearly indicated in Fig. 2.

If in setting up the economizer it is found that a coupling pipe when connected with 10 a header and the manifold, brings the vertical tubes out of proper alinement, this coupling pipe may be disconnected and another coupling pipe substituted which varies slightly from the first coupling pipe, and 15 thus by selecting the proper coupling pipe the header may be connected with the manifold so as to bring the vertical tubes into proper alinement. Thus the slight variations in different headers and coupling pipes, 20 due to inaccuracies in the manufacture of the parts, may be compensated for, and all the headers be connected with the manifolds in proper alinement. By furnishing a few extra coupling pipes when shipping the 25 parts of an economizer, the accurate connection of the parts may be insured.

In order to provide for expansion and contraction, the upper manifold is formed in sections, each section being provided with a 30 number of joint seats, so that a plurality of headers may be connected with each manifold section. The manifold sections may be provided with any desired number of joint seats. The manifold sections, as shown at 35 the left in Fig. 2, for instance, are provided with four joint seats, so that four headers may be connected to each manifold section, while the manifold section at the right in Fig. 2 is provided with eight joint seats, so 40 that eight headers may be connected to the manifold section. In order that the manifold sections may be in communication with one another without interfering with the expansion and contraction of the apparatus, 45 double couplings are provided for connecting adjacent headers with the manifold sections, and for connecting the adjacent ends of two manifold sections. As shown in Figs. 2 and 3, these double couplings consist of 50 two coupling pipes 17 and 18 united by an integral cross pipe 19. The ends of the coupling pipes 17 and 18 are provided with tapered joint seats and flanges similar to the 55 tapered joint seats and flanges on the coupling pipes 9, and these joint seats are so arranged with relation to each other that the joint seats on the ends of the pipe 18 will engage the joint seats at the end of one of the manifold sections and the joint seat 60 at the end of a header, while the joint seats at the end of the coupling pipe 17 will engage the joint seats at the end of the next adjacent header and manifold section. With 65 this form of double coupling, the tapered joint seats may be employed which rota-

tively engage each other, and the parts of the coupling may be so arranged that the parts of the joint rotate slightly with relation to each other as the coupling bends or springs during the relative movement of the 70 coupled parts, due to expansion and contraction. In case the ends of adjacent manifold sections are to be comparatively far apart, as indicated at the center of Fig. 2, a coupling may be used having a comparatively 75 long connecting pipe.

When the manifold sections are connected by the double couplings described, they are in communication with each other through the couplings, and the economizer is in condition for what is known as natural circulation 80 of the water through the pipes. In case it is desired to connect the sections of the economizer to secure what is known as forced circulation, this may be readily done 85 by removing the double coupling and substituting therefor two single coupling pipes. In such case the manifold sections will be in communication with each other through the headers and vertical tubes, and the circulation will be in one direction through the vertical tubes connected with one manifold section, and in the opposite direction through 90 the tubes connected with the next adjacent manifold section.

In order that the outlet (or inlet) pipe of the economizer may be connected with the upper manifold in different positions, according to the conditions under which the installation is made, the manifold sections 95 are provided at each end with additional joint seats 20 arranged opposite to the end joint seats with which the coupling pipes for the headers are connected. The port through these coupling seats may be closed 100 when the seats are not used to receive the joint seat of the outlet pipe, by means of caps 21.

As illustrated in Figs. 1 to 4, the coupling pipes are in the form of elbows which turn 110 through an angle of 180° so that the joint seats in the ends of the headers and the joint seats in the manifold sections are in parallel or substantially the same planes. Other forms of coupling pipes may be employed, 115 or the angle through which the coupling elbows extends may be varied as desired. For instance, coupling elbows which extend through an angle of 90° may be provided, so that the joint seats in the manifold sections 120 will be in a plane at substantially right angles to the joint seats in the ends of the headers, as indicated in Fig. 5.

In Figs. 1, 2 and 3, a novel form of combined outlet pipe and coupling pipe is 125 shown. As here shown, the coupling and outlet pipe comprises an elbow 22, having joint seats on its opposite ends adapted to engage the joint seat in the end of a header and in a manifold section to a header and 130

manifold section. This elbow is provided with an outlet extension 23 and with a flange 24 by which it may be connected with the end of a pipe leading to or from the economizer.

5 In Fig. 5 the outlet (or inlet) for the upper manifold is through a pipe 25 provided with a tapered joint seat engaging the tapered joint seat 20 in the end of the manifold opposite the joint seat through which connection is made with the end header of the economizer.

10 The nature and object of the invention having been explained, and the preferred form of the invention having been specifically described, what is claimed is:—

15 1. A fuel economizer, having, in combination, upper and lower headers, series of circulating pipes connecting corresponding upper and lower headers, the end pipes in adjacent series being connected with the headers at different distances from the ends so that the series of pipes are staggered, joint seats in the top of each of the upper 20 headers in line with the end circulating tubes, a manifold having joint seats arranged out of line with the header joint seats and corresponding thereto, and integral elbow pipes having joint seats at 25 their ends to engage the header and manifold joint seats and connect the headers with the manifold, substantially as described.

30 2. A fuel economizer, having, in combination, upper and lower headers, series of circulating tubes connecting corresponding upper and lower headers, a taper joint seat in the top of each of the upper series of headers, a manifold having corresponding 35 taper joint seats out of line with the header joint seats, and coupling pipes provided at their ends with taper joint seats to engage the header and manifold joint seats and connect the headers with the manifold, substantially as described.

35 3. A fuel economizer, having, in combination, upper and lower headers, series of circulating tubes connecting corresponding upper and lower headers, a taper joint seat in the top of each of the upper series of headers, a manifold having corresponding 40 taper joint seats out of line with the header joint seats, and coupling elbows having taper joint seats at their ends to engage the header and manifold joint seats and connect the headers with the manifold, substantially as described.

45 4. A fuel economizer, having, in combination, upper and lower headers, series of circulating tubes connecting corresponding upper and lower headers, joint seats in two adjacent headers, manifold sections having corresponding joint seats, and a coupling having joint seats for engaging the joint 50 seats of the two adjacent headers and the

joint seats of the two adjacent manifold sections, substantially as described.

5 A fuel economizer, having, in combination, upper and lower headers, series of circulating tubes connecting corresponding upper and lower headers, taper joint seats in two adjacent headers, manifold sections having corresponding taper joint seats, a coupling having taper joint seats to engage the joint seats in the two adjacent headers, and the joint seats in the two adjacent manifold sections, substantially as described.

10 6. A fuel economizer, having, in combination, upper and lower headers, series of circulating tubes connecting corresponding upper and lower headers, taper joint seats in two adjacent headers, manifold sections having corresponding taper joint seats, and a coupling elbow provided with taper joint seats to engage the joint seats in the two adjacent manifold sections, substantially as described.

15 7. A fuel economizer, having, in combination, a series of headers, manifold sections adjacent the said headers, an integral double coupling provided with four communicating joint seats arranged to connect a pair of adjacent headers with adjacent manifold sections, substantially as described.

20 8. A fuel economizer, having, in combination, a series of headers, manifold sections adjacent the said headers, a coupling comprising two pipes provided intermediate their ends with an integral connecting pipe and provided at their ends with taper joint seats, said headers and manifolds being also provided with taper joint seats whereby adjacent header sections can be 25 connected to adjacent manifolds.

25 9. A fuel economizer, having, in combination, upper and lower headers, series of circulating tubes connecting corresponding upper and lower headers, a joint seat in each of one series of headers in line with a circulating tube, a manifold provided with joint seats corresponding to the header joint seats, and coupling elbows provided with joint seats to engage the joint seats in the 30 header and manifold, substantially as described.

35 10. A fuel economizer, having, in combination, upper and lower headers, series of circulating tubes connecting corresponding upper and lower headers, a joint seat in each of one series of headers, a manifold having a series of joint seats in one side corresponding to the header joint seats, coupling pipes having joint seats to engage the header and manifold joint seats and connect the headers with the manifolds and joint seats at the ends of the manifolds opposite the joint seats for the coupling pipes, substantially as described.

11. A fuel economizer, having, in combination, upper and lower headers, series of circulating tubes connecting corresponding upper and lower headers, taper joint seats
3 in the top of each of the upper series of headers, manifold sections having corresponding taper joint seats out of line with the header joint seats, and an integral double coupling consisting of two elbows
10 having taper joint seats at their ends for engaging the joint seats of the two adjacent

headers and the joint seats of the two adjacent manifold sections and a connecting cross-pipe between the elbows, substantially as described.

15

In testimony whereof I affix my signature, in presence of two witnesses.
